US00D667023S

(12) **United States Design Patent**
Friedlander et al.

(10) **Patent No.:** **US D667,023 S**
(45) **Date of Patent:** ** *Sep. 11, 2012

(54) **DISPLAY DEVICE WITH USER INTERFACE**

(75) Inventors: **Steven Friedlander**, San Diego, CA (US); **Sabrina Tai-Chen Yeh**, Laguna Beach, CA (US)

(73) Assignee: **Sony Corporation**, Tokyo (JP)

(*) Notice: This patent is subject to a terminal disclaimer.

(**) Term: **14 Years**

(21) Appl. No.: **29/350,167**

(22) Filed: **Nov. 12, 2009**

(51) LOC (9) Cl. 32-00

(52) U.S. Cl. **D14/487**

(58) **Field of Classification Search** D14/485-495; 715/700-867

See application file for complete search history.
